SPORT FISHING REEL

Richard K. Sutz, 5800 Arlington Ave.,
Riverdale, N.Y. 10471

Filed Nov. 27, 1968, Ser. No. 14,705

Term of patent 14 years

Int. Cl. D22—06

U.S. Cl. D22—25

FIG. 1 is a perspective view of a sport fishing reel, showing the top and one side of the reel.

FIG. 2 is a perspective view showing the top and opposite side of the reel.

FIG. 3 is a side elevational view of the reel.

FIG. 4 is a bottom plan view of the reel.

I claim:

The ornamental design for a sport fishing reel, as shown.
